United States Patent Office.

JAMES M. PEIRCE, OF MOKENA, ILLINOIS.

Letters Patent No. 78,004, dated May 19, 1868; antedated April 30, 1868.

IMPROVED BLIND-SLAT FASTENING.

The Schedule referred to in these Letters Patent and making part of the same.

TO ALL WHOM IT MAY CONCERN:

Be it known that I, JAMES M. PEIRCE, of Mokena, in the county of Will, and State of Illinois, have invented a new and useful Improvement for Fastening Blind-Slats, to prevent them from being opened from the outside when closed; and I do hereby declare that the following is a full, clear, and exact description of the construction and operation of the same, reference being had to the annexed drawings, making a part of this specification, in which—

Figure 1 is a view of the fastener or button for blind-slats.

A shows the upper end of the fastener, which is set firmly against the lower end of the cross-bar to the slats. It is then screwed to the bottom-piece of the blind at B. The pin D is inserted, or the spring E is used, or its equivalent, to prevent the fastener from being moved on the outside.

To open the slats, draw the pin D or raise the spring E, and turn the fastener to one side, which leaves the slats free to move.

The fastener can be made of iron or other metal, or of wood, and thereby secure the slats and blinds from being opened from the outside.

What I claim as my invention, and desire to secure by Letters Patent, is—

The use of a fastener or button, A, also the spring E, and the pin D, as herein described, to prevent blind-slats or blinds from being opened on the outside.

JAMES M. PEIRCE:
